UNITED STATES PATENT OFFICE.

MAURICE E. BROWN, OF MARINETTE, WISCONSIN.

METHOD AND APPARATUS FOR PRESERVING POSTS.

Application filed August 28, 1924. Serial No. 734,812.

My invention relates to improvements in perforators for posts and similar articles, and methods and apparatus for preserving posts.

5 In the art relating to the preservation of wooden posts, etc., it is common to apply creosote or other preservatives in liquid form either by dipping the posts in the liquid or applying the liquid thereto by 10 means of a brush or through a spray nozzle. In some instances the preservative has been driven into the wood by the application of pressure within a retort, or by the application of both pressure and heat. The expense of driving the preservative into the pores of the wood by the application of pressure, or pressure and heat, is prohibitive for ordinary purposes and particularly so where the posts to be treated are of considerable length as is the case with telephone 15 and telegraph posts. Therefore, a common practice is to merely coat the surface of the wood, although it is known that in such cases the preservative does not penetrate to any great depth, and the preservative is quickly removed by natural washing and leaching processes.

The object of this invention is to provide effective method means whereby wooden 30 posts and similar articles with uneven surfaces may be quickly provided with a multitude of slits or perforations, all of the same depth and of a character which will not materially affect the strength of the post, whereby a liquid preservative will be permitted to enter the pores of the wood across the cellulose binder walls to such a substantial depth as to prevent it from being washed or leached out of the wood under ordinary 35 conditions.

More particularly stated, it is an object of this invention to provide a wood perforating machine which has a series of rotary perforating units each adapted to be independently pressed against the wood, whereby when the post or other article is rotated, each perforating unit will penetrate the wood at a multitude of points in an annular zone or belt preparatory to the application 40 of the preservative.

In the drawings:

Figure 1 is a fragmentary view showing my improved machine, partly in section and partly in side elevation.

55 Figure 2 is an end view of the same with

a portion broken away to show the detent for controlling the rotation.

Figure 3 is an enlarged view of a portion of the surface of a post after it has been perforated.

60 Figure 4 is a sectional view drawn on line 4—4 of Figure 2.

Figure 5 is a plan view of the portion of the machine illustrated in Figure 1.

Figure 6 is a detailed view of a portion 65 of the periphery of the rotary member of one of the rotating units.

Figure 7 is a detailed view showing a portion of said rotary member in side elevation and partially broken away to show the 70 means for inserting and retaining the individual perforating devices.

Figures 8, 9 and 10 are detailed views of one of the perforating devices.

Figure 11 is an elevation showing the improved machine in operation as viewed from one end of the log and of the holder for the series of perforating units.

Figure 12 is a detail showing the relative positions of the successive wheel controlling 80 detents.

Like parts are identified by the same reference characters throughout the several views.

A holder 1 of a length substantially equal 85 to the length of that portion of the post which it is desired to perforate is provided with centrally disposed cylindrical projections 2 whereby it may be supported by the forked arm 3 (Figure 1) of a suitable supporting and pressure applying device such, for example, as the slide 5 adjustable by means of the screw 6 and movable along a supporting column or standard 7. The slide has an arm 8 which supports the fork 3 and the latter is divided at 9 whereby the fork may be assembled in engagement with the projections 2 and then secured together by bolts 10. Each fork arm 3 has an aperture to receive the associated projection 2 whereby the holder is pivotally connected with the fork.

The holder is provided with a series of vertically extending apertures to receive the shanks of the perforating units. Each shank 105 comprises two members 12 and 13 which are secured together by bolts 14, the heads of which are countersunk in the member 13. At their lower ends these shanks are provided with fork arms 17 and 18 having interlock- 110

ing heads 19 and supporting axle members 20 upon which a perforating wheel 21 is journaled. The shank members and fork heads are separable to facilitate inserting 5 and removing the wheels and their bearings 22.

Each shank is supported within the holder 1 by a bolt 24 (Figure 1), the head 25 of which rests upon a socketed cap 26 fitted to 10 an enlargement of the shank receiving bore in the holder and having its lower margin resting upon the shoulder 27 at the base of said enlargement. The lower end portion 28 is threaded and engaged in a threaded socket 15 formed in the upper end of the associated shank and a coiled compression spring 30 is interposed between the upper end of the shank and the head of the cap member 26, whereby the shank is pressed downwardly by 20 the spring and normally held in a position with the head 25 of the bolt engaging the head of the cap 26. Each wheel 21 with its associated shank is therefore permitted to move upwardly independently of every other 25 wheel in the set or series under pressure sufficient to compress the spring 30. The resistance to such upward movement will of course increase as the spring is compressed.

Each of the wheels 21 is provided with a 30 rim 35 having notched peripheral flanges 36 projecting outwardly in radial planes. Each notch has the general form of a key 35 hole slot, the inner or base portion 37 of the notch being cylindrical in form with a relatively narrow opening to the periphery of the rim flange. The walls 38 of these openings diverge in the direction of the periphery. The notches are slightly oblique to a plane which includes the axis of the wheel 40 and they are paired in the respective side flanges 36 of the wheel rim so as to permit insertion of a cross pin or rod 39 in each pair of notches with the ends of the pin held against radial movement by the respective 45 flanges 36. The rods 39 of each wheel 21 comprise a plurality of peripheral portions of their respective wheels and are eccentric to the axis (not at the center) thereof. Perforating blades 40, somewhat similar in form 50 to the wards of a key, project outwardly or radially from the end portions of the cross pins or rods 39 and extend beyond the peripheries of the rim flanges 36 sufficiently to enable them to penetrate the wood to the 55 desired depth when rolled in pressure contact with the surface of the post to be perforated. The divergent walls 38 of the notches allow a limited oscillatory movement of the perforating blades 40 and their 60 associated cross pins 39 within the slots. After the cross pins have been inserted as above described, they are held from sliding out transversely of the wheel by a set of retaining rings 41 which may be secured to 65 the rim of the wheel by screws 42. By re-

moving one of these retaining rings the pins 39 with their associated perforated blades may be removed to allow the perforating blades to be sharpened or replaced.

Each perforating blade is preferably rectangular or substantially rectangular in cross section, as best shown in Figures 8, 9, and 10, and the outer extremities of the blades are beveled to form oblique cutting edges 45, pitched or inclined in the same direction as 70 the rods or pins 39 with reference to planes which include the axis of the wheel. In other words, the cutting edges of the perforating blades have a pitch substantially in 75 a helical line and the degree of the pitch is 80 determined by the inclination of the edge of the blade and the inclination of its associated supporting cross pin or rod 39.

In order that the perforations made by each successive wheel may be uniformly advanced with reference to longitudinal lines through perforations made by the preceding wheel, the wheel supporting forkheads 19 are provided with detents 48 mounted in recesses 49 with one end pivotally connected 90 to the cross head 19 by a pivot pin 50. The other end of each detent is inturned and provided with a roller 51 which is received between the rim flanges 36 of the wheel and is 95 adapted to yieldingly engage between successive cross pins or rods 39. A coiled spring 54 is socketed in the head 19, the socket also receiving a guiding plunger 55 which bears upon the detent 48 to yieldingly 100 press the roller 51 in the direction of the rim 100 of the wheel.

It will be obvious that in order for a perforating wheel to rotate, its several cross rods or pins 39 will have to act successively upon roller 51 to elevate such roller slightly 105 against the compression of the respective spring 54. As the roller passes over each of the cross pins 39 it is pressed by its spring into the next succeeding space between pins 39. Inasmuch as the perforating wheels are 110 not positively driven, each such wheel will tend to be brought to rest by the pressure of the detent spring holding roller 51 into what may be termed the interdental space 115 between pins 39. When the machine is at rest each of the detent rollers will find one such interdental space in its associating perforating wheel and thus the teeth of the 120 perforating wheels, acted on by aligned detent rollers, will be found in substantial 125 alignment.

The detents associated with successive wheels are preferably advanced or retracted with reference to those of the next adjacent wheel so that the perforations produced by 125 one wheel will be substantially in longitudinal lines extending midway between corresponding perforations produced by either one of the adjacent wheels. In the construction shown this may be accomplished either 130

by placing the pivot pin of one detent ⁵² of an inch forwardly or backwardly with reference to the position occupied by the next pin, or if desired, the pivot pins may be aligned and each alternate detent may be made ⁵² of an inch shorter than the intermediate detents. In this manner the perforations made by the series of wheels may be staggered or caused to follow a helical line

10 around the post or pole from one end of the perforated zone to the other substantially as illustrated in Figure 3.

In Figure 4 it will be observed that the pivot pin 50 is mounted in a projecting member 56 on that portion of the head piece which is associated with shank section 13, the detent being engaged in a slot or slit formed in the projection 56, as clearly shown in Figure 1. A lip 57 on the other portion 20 of the head piece connected with the shank section 12, is utilized to prevent the pivot pin 50 from slipping out of its socket when the parts are assembled.

In operation, the wheels are applied to a post 60 which may be supported upon rollers 61 and 62. The rollers 61 may be positively driven from any suitable source of power. In the construction shown the roller shaft 61' is provided with a sprocket wheel 63 whereby it may be actuated from a pulley 65 and driving sprocket wheel 66 through a sprocket chain 67.

With the construction shown in Figure 11 the holder 1 is supported above the post 60 by the slide 5. A downward pressure is applied to the holder by means of the screw 6 whereby all of the wheels are brought into operative relation to the post 60 and the desired degree of normal pressure is applied. 40 This pressure will in each case be sufficient to partially compress the springs 30 and raise the bolt heads 25 above the heads of the caps 26 whereby each wheel is yieldingly pressed against the post with sufficient pressure to ensure the penetration of the perforating blades into the wood. Thereupon, the post 60 may be rotated by means of the active roller or rollers 61 and each perforating wheel will exert its pressure to drive the 45 associated blades into the post independently of every other wheel since the pressure of each wheel will then be determined primarily by its associated spring 30.

The blades 40 form slits in the wood which 55 extend generally along lines longitudinal to the post but with a sufficient oblique pitch to cut across the cellulose walls of the pores to a sufficient extent to allow entry of the preservative to a considerable number of pores with a minimum of injury to the fibres. The abruptly beveled surfaces of the blades tend to press the fibres apart. The pitch of the pins or rods 39 is such as to cause the slits produced at one end thereof 60 to assume a staggered relation with reference

to those produced by the blades at the other end thereof. The oblique pitch of the cutting edge of each blade also facilitates its entry into the curving surface of the post, since the blade can enter only one point on the surface at any given instant if the surface is a true curve and the pressure is therefore progressively concentrated upon different portions of the cutting edge. 70

It will be understood that for telephone poles, fence posts and other posts used under similar conditions the areas particularly exposed to decay are those in the vicinity of the surface of the ground, both above and below that surface. For piling, and for wooden articles to be more or less horizontally disposed along the surface of ground or water, the entire surface may be treated in accordance with my improved method in which I open pores at short intervals along the surface between the ends and insert a preservative in the openings and into the pores, where it is less subject to delusion and wash and where it can slowly permeate the wood under varying conditions of heat 90 and moisture. The preservative may be applied and inserted by dipping the post in liquid preservative or by applying the preservative to the slotted area of the post by a brush or by spraying it thereon, preferably 95 under pressure or by any other suitable means of application.

I claim:

1. A wood perforator comprising the combination of a holder, an adjustable support therefor, a set of rotary wheels provided with peripherally projecting perforating devices, and means for rotating a wooden post in pressure contact with said perforating devices, each of said wheels being adapted to yield independently of the others in accordance with the pressure exerted thereon and each of said perforating devices being adapted to oscillate to a limited extent substantially in the plane of wheel rotation to allow it to be withdrawn from the wood by the rotating wheel substantially along the line of penetration. 105

2. A wood perforator comprising the combination with means for supporting and rotating a post, of a rotatable perforating member provided with relatively short pointed blades rotating with said member at substantially the peripheral rate of rotation of a post supported by said means, a standard carrying said member with its axis substantially parallel to the axis of such a post, and means for maintaining the blades of said member held to the periphery of such a post in pressure contact, said blades being approximately radial with respect to said member and being independently oscillatable in the direction of rotation of said member whereby to be adapted to enter the periphery of such a post substantially along radial lines 115 120 125 130

and to leave such a post along substantially the line of entry.

3. The combination with a vertically adjustable support, of a holder pivotally connected therewith, a set of wheels provided with wood penetrating projections extending outwardly from their peripheries, forked supports provided with axles for said wheels and having shanks socketed in the holder, 10 means for supporting the shanks in the holder sockets, means for applying resilient pressure to the shanks to hold them in partially extended positions in which each may have yielding movement independently of 15 the others, and means for rotating a wooden object, such as a post, in pressure contact with said projections.

4. In a device for providing wooden posts with openings for preservative material, the 20 combination with a set of rotatable perforating wheels provided with outwardly projecting blades and having eccentric peripheral portions, of resiliently yieldable detent members contacting with such eccentric 25 peripheral portions and adapted to maintain a plurality of said wheels yieldably in predetermined relative positions of rotation.

5. In a device for providing wooden posts with openings for preservative material, the 30 combination with means for supporting and rotating a post, of a set of idly rotatable perforating wheels having eccentric portions and independently pressed in the direction 35 of said means to contact with a post supported thereby and receive motion therefrom, together with detents acting individually on eccentric portions of said wheels and adapted to maintain said wheels in predetermined positions of relative rotation.

40 6. In a post perforator, the combination of a wheel having a rim provided with transversely extending anchorage recesses, obliquely pitched along helical lines, oscillatory members anchored in said recesses and 45 provided at their respective ends with blades, the cutting edges of which are additionally pitched in an oblique direction from a transverse plane through the axis of the wheel, and means for rotating a post in pressure 50 contact with said blades.

7. In a device for providing wooden posts with openings for preservative material, the 55 combination with means for supporting and rotating a post, of a set of idly rotatable perforating wheels having eccentric portions and independently pressed in the direction of said means to contact with a post supported thereby and receive motion there-

from, together with detents acting individually on eccentric portions of said wheels and adapted to maintain said wheels in predetermined positions of relative rotation, 60 said wheels having transversely slotted peripheries and penetrating blades respectively anchored in the slots of said peripheries and 65 projecting outwardly therefrom for limited oscillation with respect to said wheels.

8. The method of preserving wooden posts, consisting in rotating the posts in contact with a multiple series of perforating 70 devices having blades disposed obliquely to the axis of rotation of the posts and resiliently supporting each series of perforating devices for movement independently of the next and controlling their rotation to produce perforations which are staggered with reference to the perforations produced by 75 the next series of such devices.

9. In a device of the character described, the combination with means for supporting 80 and rotating a post, of a set of marginally flanged wheels independently supported and pressed toward said means whereby to engage a post supported thereon to be rotated thereby, anchors extending transversely between the flanges of such wheels, perforating teeth carried by said anchors, and a detent associated with each such wheel and yieldably pressed in the direction thereof, each such detent including a portion adapted 85 to engage said anchors, said teeth being adapted to maintain said wheels in predetermined relative positions of rotation.

10. In a device of the character described, the combination with means for supporting 90 and rotating a post, of a set of marginally flanged wheels independently supported and pressed toward said means whereby to engage a post supported thereon to be rotated 100 thereby, anchors extending transversely between the flanges of such wheels, perforating teeth carried by said anchors, and a detent associated with each such wheel and yieldably pressed in the direction thereof, each such detent including a portion adapted 105 to engage said anchors, said teeth being adapted to maintain said wheels in predetermined relative positions of rotation, certain of said detents being pressed in the direction of rotation of said wheels with 110 respect to others of said detents for a distance equivalent to a fractional part of the peripheral distance between such teeth beyond others of said teeth.

MAURICE E. BROWN.
